UNITED STATES PATENT OFFICE

GEORGE H. DAWSON, OF CAMBRIDGE, MASSACHUSETTS, ASSIGNOR TO WILSON-JONES COMPANY, OF CHICAGO, ILLINOIS, A CORPORATION OF MASSACHUSETTS

DRAWER PULL AND LABEL HOLDER

Application filed August 11, 1930. Serial No. 474,608.

This invention relates to a combined drawer pull and label holder adapted for use upon a visible index drawer, and concerns itself primarily with the manner of incorporating the same with the drawer.

5 The invention comprises the novel structure and combination of parts hereinafter described and more particularly pointed out and defined in the appended claims.

10 In the accompanying drawings which illustrate a preferred form of this invention and in which similar reference numerals refer to similar features in the different views:

Fig. 1 is a fragmentary top plan view of 15 a cabinet drawer having a pull out and label holder involving this invention.

Fig. 2 is a front elevational view of the drawer showing the pull out and label holder.

Fig. 3 is a fragmentary sectional view 20 taken upon the line III—III of Fig. 2 with parts broken away.

Fig. 4 is a fragmentary sectional view taken upon the line IV—IV of Fig. 2.

In the drawings, only those parts of the 25 cabinet drawer have been shown which cooperate with this invention. This drawer consists of a metal bottom plate 1 and sides 2 which consist of folded metal plates having spaced walls 3 as shown in Fig. 1. The front

30 end of the drawer is closed by a plate 4 having inwardly directed flanges 5 that are located between the walls 3 of the sides of the drawer and welded or secured to the inner wall thereof. This front plate also has a lower forwardly extending flange 6 and an upper forwardly extending flange 7 which slopes upwardly. In referring to Fig. 3, it will be noted that the bottom 1 of the drawer projects forwardly beyond the front plate 4 and that the flange 6 is slightly spaced thereabove.

The drawer pull and label holder consists of a sheet metal member 8 having a front curved face with label exhibiting windows or 45 openings 9 and a hand or finger slot 10 therebetween. This drawer pull has a lower rearwardly extending flange 11 that fits between the flange 6 of the front plate and the bottom 1 of the drawer, and an upper rearwardly 50 directed flange 12 that rests upon the flange 7.

These flanges 11 and 12 of the drawer pull are secured or welded to the flanges of the front plate 4.

Suitable pieces of mica or celluloid 13 or the like may be inserted from the ends of the label holder for closing the openings 9 and forming windows for the labels which may be inserted the same way.

It will be apparent that the drawer pull and label holder is firmly attached to the front plate which in turn is firmly attached to the sides of the drawer so that the same will resist any severe pull upon the drawer without working loose.

I am aware that many changes may be made, and numerous details of construction may be varied through a wide range without departing from the principles of this invention, and I therefore do not purpose limiting the patent granted hereon, otherwise than necessitated by the prior art.

I claim as my invention:

1. The combination with a drawer having side walls, of a front end plate therefor having rearwardly extending flanges attached to said side walls, said plate having an upper and a lower forwardly extending flange and a drawer pull and label holder attached to said last mentioned flanges.

2. A drawer having a front end wall with upper and lower forwardly directed flanges and a label holder having parts welded to said flanges.

3. In a drawer, a front end wall having forwardly directed spaced flanges and a drawer pull and label holder having rearwardly directed flanges attached to said first mentioned flanges.

In testimony whereof I have hereunto subscribed my name at Cambridge, Middlesex County, Massachusetts.

GEORGE H. DAWSON.
